HANDLE FOR CUTLERY ARTICLES

Filed March 28, 1922

Patented June 5, 1923.

1,457,606

UNITED STATES PATENT OFFICE.

JOSEPH ANTHONY SCHLEHR, OF CHICAGO, ILLINOIS.

HANDLE FOR CUTLERY ARTICLES.

Application filed March 28, 1922. Serial No. 547,589.

To all whom it may concern:

Be it known that I, JOSEPH A. SCHLEHR, a citizen of the United States, residing at Chicago, in the county of Cook and State 5 of Illinois, have invented certain new and useful Improvements in Handles for Cutlery Articles: and I do declare the following to be a full, clear, and exact description of the invention, such as will enable others 10 skilled in the art to which it appertains to make and use the same.

This invention relates to an improved handle for articles of cutlery, such as knives, forks, cleavers, and the like.

15 The principal object of the invention is to provide a novel handle of this class which is composed of duplicate sections placed against the opposite sides of the metal body, these sections being shaped to render 20 them neat and being connected with the body by novel means which is practically invisible to the eye. Hence, this novel fastening means for the handle sections obviates the necessity of employing unsightly 25 rivets and fasteners such as are commonly used for this purpose.

Speaking more specifically, it is one of the objects of the invention to place keys on opposite sides of the metal body so that 30 they extend longitudinally thereof, and to then form keyways in the inner faces of the handle sections for reception of these keys, these keyways extending through the opposite ends of the handle sections and 35 permitting the latter to be slipped onto the keys and retained in position by any suitable means.

Other objects and advantages of the invention will be apparent during the course 40 of the following description.

In the accompanying drawings forming a part of this specification and in which like numerals are employed to designate like parts throughout the same:

45 Figure 1 is a side elevational view of a knife blade equipped with a handle constructed in accordance with this invention.

Figure 2 is a central longitudinal section taken on the line 2—2 of Fig. 1.

50 Figures 3 and 4 are transverse vertical sections taken on the lines 3—3 and 4—4 respectively of Fig. 1.

Figure 5 is a side elevational view showing one of the keys and a handle section 55 partially slid thereon.

Figure 6 is a side elevational view of a

slightly modified form of the invention showing the handle section in the act of being slid onto the key.

Figure 7 is a transverse vertical section 60 taken on the line 7—7 of Fig. 6.

For the purpose of illustration, I have shown the improved handle as being applied to a knife blade. However, as before indicated, the improved handle is not restricted 65 to this particular use, because it can be used on various other articles. Therefore, the following description is not limiting.

Proceeding with the detailed description, 70 it will be seen that the numeral 1 designates a knife blade and the numerals 2 designate duplicate handle sections placed against the opposite sides thereof adjacent one end in the usual way. These handle sections may be composed of any suitable

75 material and may be shaped in any way to render them neat and attractive. Broadly speaking, the means for securing the handles in place comprises, as before indicated, 80 keys and keyways. In carrying out the invention I employ two different kinds of fastenings. The preferred form of the invention is shown in Figs. 1 to 5 inclusive.

85 Directing attention first to these figures, it will be seen that the keys, which are designated by the numerals 3 are simply in the form of relatively thin strips of metal secured to the knife blade intermediate the upper and lower edges thereof. These keys extend from one end of the blade to a point 90

near the center. As seen, the longitudinal edges of the metal strips are bent outwardly from the respective surfaces of the blade to provide divergent flanges 4 which are intended to extend into divergent longitudinal slits 5 formed in the inner faces of the handle sections 2. The handle sections are also equipped with shallow recesses 6 between these slits to accommodate the thickness of the metal strips. These recesses and 100 slits extend through the opposite ends of the handle sections.

It is of course necessary to provide means for holding the handle sections against longitudinal slippage after they are once in 105 place. Although any other means could be employed for accomplishing this end, I prefer to provide the aforesaid metal strips with relatively small tongues 7 at their opposite ends. After the handle sections are 110 in place, the tongues are bent laterally outward against the adjacent ends of the han-

dle sections as clearly shown in Figs. 2 and 4. With this arrangement, the handle sections are held securely in place. However, if one of the sections should become broken and required replacement, the tongue at the outer end thereof could be bent straight to permit the broken section to be slipped off of the retaining key.

It has been before intimated that I also 10 employ another construction of connecting means in carrying out this invention. I therefore direct attention to Figs. 6 and 7 wherein the second form of the invention is illustrated. In these figures, the numeral 15 1^a designates the blade of a knife and the numerals 2^a, the two handle sections. The handle sections in this form of the invention are formed in their inner faces with relatively deep grooves or keyways 6^a, the side 20 walls of which are inclined as at 8 to accommodate the inclined sides of the dovetail keys 9 which are received in these grooves. It is to be noted that the grooves adjacent the outer ends of the handle sections are widened somewhat the same as the keys are. Hence, the sliding movement of the handle sections is limited in one direction, and when they are forced to the inner 25 end of the knife blade, they are securely held against slippage by friction.

By carefully considering the description in connection with the drawings, persons familiar with devices of this class will doubtless be able to obtain a clear understanding 30 of the invention. Therefore, a more lengthy

and detailed description is deemed unnecessary.

Since probably the best results may be obtained with the construction and arrangement herein shown and described, this is 40 taken as the preferred embodiment of the invention. However, I wish it to be understood that minor changes coming within the scope of the invention as claimed may be resorted to if desired. 45

I claim:

1. An article of cutlery comprising a body, a longitudinal key secured to one side of said body, having retaining tongues at its opposite ends, and a handle section formed in 50 its inner face with a keyway to accommodate said key, the retaining tongues being designed to be bent against the ends of the handle section to retain the latter in place.

2. An article of cutlery comprising a body, 55 a metal strip secured to one side of said body and extending from one end to a point adjacent the center, the opposite longitudinal edges of said strip being bent laterally away from the adjacent face of the body to 60 provide divergent retaining flanges, a handle section having a groove in its face to accommodate said strip and provided with divergent slits for reception of said flanges, and co-acting means between the opposite 65 ends of the strip and handle to retain the latter against longitudinal slippage.

In testimony whereof I have hereunto set my hand.

JOSEPH ANTHONY SCHLEHR.
